UNITED STATES PATENT OFFICE.

FREDERICK W. RENWICK, OF CAMDEN, NEW JERSEY, ASSIGNEE OF ONE-HALF TO
JOHN S. LATTA, OF PHILADELPHIA, PENNSYLVANIA.

WIRELESS RECEIVING-APPARATUS CABINET.

Application filed July 24, 1924. Serial No. 727,332.

To all whom it may concern:

Be it known that I, FREDERICK W. RENWICK, a citizen of the United States of America, residing at Camden, in the county 5 of Camden and State of New Jersey, have invented certain new and useful Improvements in Wireless-Receiving-Apparatus Cabinets, of which the following is a specification.

This invention relates to new and useful 10 improvements in wireless receiving apparatus cabinets.

The primary object of the invention is to provide a cabinet of the above mentioned 15 type which is adapted for being held or supported in contact with a vertically extending surface.

A further object of the invention is to provide a cabinet which is suitable for being 20 supported by a piece of movable furniture.

A still further object of the invention is to provide a cabinet for a wireless receiving apparatus having a remote control unit, as set forth in the application for remote control unit for wireless receiving apparatus, filed by F. W. Renwick, July 19, 1924, Serial 25 No. 726,966, the said wireless apparatus cabinet being especially adapted to be secured to a talking machine cabinet, for the 30 purpose of permitting the remote control unit to be housed within the latter cabinet when not in use.

Another object of the invention is to provide a cabinet of the above mentioned type 35 which is especially adapted for supporting the various instrumentalities necessarily employed for constituting a receiving set and for permitting ready access to be had to certain portions of the set.

Other objects and advantages of the invention will be apparent during the course 40 of the following description.

In the accompanying drawings forming a part of this specification and in which like 45 numerals are employed to designate like parts throughout the same,

Figure 1 illustrates a perspective view of the wireless receiving apparatus cabinet embodying this invention properly mounted 50 upon a talking machine cabinet and further illustrates the manner of arranging the instrumentalities employed for constituting a receiving set,

Figure 2 is a fragmentary view showing a 55 portion of the talking machine cabinet in

section with the wireless receiving apparatus cabinet shown attached thereto in full lines and with the remote control unit, referred to above, housed within the talking machine cabinet,

Figure 3 illustrates a side elevational view of the wireless receiving apparatus cabinet embodying this invention and further illustrates the manner of attaching the cabinet to a talking machine cabinet,

Figure 4 illustrates a fragmentary front elevational view of the wireless receiving apparatus cabinet,

Figure 5 illustrates a longitudinal sectional view of the means employed for attaching the wireless receiving apparatus cabinet to a piece of furniture, and

Figure 6 illustrates a fragmentary elevational view of the bracket element carried by the wireless receiving apparatus cabinet.

In the drawings, wherein for the purpose of illustration is shown a preferred embodiment of this invention, the numeral 5 designates the wireless receiving apparatus cabinet in its entirety. This cabinet includes a bottom wall 6, side walls 7 and 8, a rear wall 9 and a top wall 10 which includes a hingedly mounted door or section 11. The front of the cabinet 5 is intended to be closed by the hingedly mounted door 12 which is normally retained in its closed position by the screws 13, see Figs. 3 and 4. This door 12 is only to be opened when repairs or changes are to be made to the instrumentalities housed within the cabinet, the door or section 11 formed in the top wall 10 being employed for making adjustments necessary for successfully operating the receiving set.

The interior of the cabinet 5 is divided into a plurality of compartments by the shelves 14, 15 and 16, while the shelves 15 and 16 are provided with partitions 17 and 18 for forming four, substantially equi-sized compartments within which such instruments as transformers, B batteries, etc. may be housed. An elongated compartment 19 is formed by a partition 20 which extends between the shelves 14 and 16 and flushly engages one transverse edge of the shelf 15 and is provided for housing the connections made between the various instrumentalities housed within the cabinet and the jacks or terminals carried by the panel 21 embedded in the side wall 7 of the cabinet.

A removable box 22 is adapted to be positioned upon the bottom wall 6 and is employed for carrying the battery cells 23 and a battery charger or rectifier, not shown, 8 should the same be employed. It will be seen that the upper shelf 14 is suitable for supporting the various vacuum tubes 24 in such a position that they may be readily reached by opening the small door 11 in 10 the top wall 10. A tuning coil 25 may also be positioned within this upper compartment so that the tuning slide or adjustment element 26 may be reached by opening the top door 14. The side wall 7 is further provided with a metallic insert 27 having a bulb's eye 28 carried thereby for permitting the electric bulb 29, associated with the batteries 23 and charging circuit for indicating when the same is in operation, to be viewed 15 without necessitating the opening of the large front door 12. This insert 27 is further provided with a circular series of apertures 30 by means of which fumes discharged by the battery cells may find their 20 way out of the cabinet, the said apertures also providing means for ventilating the interior of the cabinet.

In the various figures, this wireless receiving apparatus cabinet is illustrated as 25 being attached to a talking machine cabinet 31. It is to be understood that while this cabinet 5 is especially adapted for being connected to a talking machine cabinet, it may as readily be secured to any other piece of 30 furniture having at least one vertically extending surface or it may be mounted upon a door or a wall of a room. The mounting of this cabinet 5 upon the back wall of a victrola, in which position it will be very inconspicuous, may best be accomplished by employing tubular bolts 32 which are flanged at one end, as at 32', and externally screw threaded at the other end 33 for the reception 35 of the clamping nut 34, see Fig. 5. These bolts may be inserted through holes drilled in the wall of the cabinet 31 and pass through the apertures 35 formed in the bracket straps 36 suitably secured to the rear 40 wall 9 of the cabinet 5.

50 In Figs. 1 and 2 there is shown a remote control unit 37, which is embodied in an application referred to above, connected to

suitable taps carried by the panel 21 by the cable 38 which extends into the upper or turn-table compartment 39 of the talking machine cabinet 31 through one of the tubular bolts 32. In Fig. 1 this remote control unit 37 is illustrated as being positioned upon the top of the talking machine cabinet 31 while in Fig. 2 the remote control unit 37 is illustrated as being housed within the turn-table compartment 39 of the cabinet 31. These two figures are intended to illustrate the possibility of housing the remote control unit 37 within the talking machine cabinet 31 when the former is not in use. The tone arm 40, see Fig. 2, of the talking machine is intended to be employed for having a phone unit 41 suitably attached to its sound box for permitting the sound box, tone arm, and 70 horn, not shown, to be used as a loud speaking unit. This phone unit 41 is intended to be attached to the suitable terminals on the panel 21 by a cable which extends into the compartment 39 through the remaining tubular bolt 32.

It is now believed that all of the advantages possessed by this invention have been fully disclosed. It, also, is to be understood that the form of this invention herewith shown and described is to be taken as a preferred example of the same, and that various changes in the shape, size, and arrangement of parts may be resorted to without departing from the spirit of the invention or the scope of the subjoined claim.

Having thus described the invention, I claim:

In a device of the type described, a cabinet adapted for housing music producing mechanism, a cabinet adapted to house a wireless receiving set, a portion of one wall of said latter cabinet being constructed for the reception of jacks and other electrical connector elements, and tubular members passing through portions of both of said cabinets for connecting the receiving set cabinet to the music mechanism housing cabinet and for permitting wires attached to the electric connector elements to pass therethrough into the last mentioned cabinet.

In testimony whereof I affix my signature.

FREDERICK W. RENWICK.
